AQUARIUM

Irving Schlesinger, Laguna Niguel, and Charles Fleenor, Laguna Beach, Calif., assignors to South Bay Treasure, Inc., doing business as Treasure Industries, Hawthorne, Calif.

Filed Mar. 27, 1972, Ser. No. 238,732

Term of patent 14 years

Int. Cl. D30—02

U.S. Cl. D30—9

FIG. 1 is a left side, top and front perspective view of an aquarium, showing our new design; and

FIG. 2 is a top plan view thereof.

The rear and right side, not shown, are plain and unornamented. The figures are shaded to indicate contrast in appearance, a portion of FIG. 1 being diagonally lined to indicate transparency.

We claim:

The ornamental design for an aquarium, substantially as shown and described.
